UNITED STATES PATENT OFFICE.

OTTO WEINSTEIN, OF BOSTON, MASSACHUSETTS, ASSIGNOR TO STANDARD NECKWEAR COMPANY, OF BOSTON, MASSACHUSETTS, A CORPORATION OF MASSACHUSETTS.

NECKTIE AND METHOD OF MAKING THE SAME.

Application filed November 17, 1926. Serial No. 148,867.

This invention relates to a new improvement in bow neckties and in methods of making up bow neckties.

One feature of the invention pertains to a bow necktie which closely simulates in appearance bow neckties which are tied by hand and those which are of the better grade of ready-tied neckties, but which is distinctive in that a very substantial saving in goods is effected without detracting from the solid and compact appearance of the tie.

Another feature of the invention is the provision of a bow necktie having the outward appearance of at least three or four folds or layers of material but which throughout most of its length is formed of only two walls or main body portions from top to bottom.

Another feature of the invention is the manner in which the end portions are used to simulate folds of goods and at the same time these portions serve to stiffen the ends of the tie and thus to maintain its shape.

One particularly important phase of the invention relates to the method of handling the strip of goods of which the necktie is formed. The details of this method include the manner of preparing the folds which in the completed tie constitute the tucked-in ends.

The above and other details and advantages will be described and claimed in the following specification and claims, and illustrated in the accompanying drawing, in which:—

Figure 1 represents a front view of the necktie of this invention, thus closely resembling the usual bow tie;

Figure 1^a is a top plan view looking down on the tie shown in Figure 1;

Figure 2 is a sectional view, rather diagrammatic, taken on the line 2—2 of Figure 1;

Figure 3 is a view taken on the line 3—3 of Figure 1;

Figure 4 is a view of the rear side of the strip of goods used in forming the bow tie, and showing its tubular construction, the adhesive strip being broken away to show the inner lining;

Figure 5 is a sectional view taken on the line 5—5 of Figure 4;

Figure 6 is a diagrammatic view showing the first step in the method of treating the tubular strip to prepare a tuck;

Figure 7 indicates the next position of the strip after the tucked portions have been prepared; and

Figure 8 represents the final position of the respective parts of the tie indicating the position of the tucked-in ends between the outer walls of the tie.

Heretofore, ready-made bow ties have usually been formed of goods arranged in a manner copying as closely as possible the hand tied bow tie or else they have provided a plurality of loops in each wing of the bow. The first form which simulates the hand tied arrangement includes a loop and an end in each wing. With these arrangements, there is ordinarily at least three complete walls of built up structure in the wing of each side of the tie.

By the use of the present invention, it is now possible to effect the saving of approximately one-third of the facing material of bow ties. The part of the tie which heretofore has comprised the end of the hand tied variety is done away with altogether and the tie uses looped ends having the appearance of two loops at each end. Throughout the major portion of the length, the tie of the present invention consists of only two main layers or folds, this pertaining to complete thicknesses and not merely to fabric thicknesses.

By preparing the tie in accordance with the present method, a further saving of approximately fifteen percent of the goods is effected because the reverse face of the tie is never on the exterior and it is thus possible to leave a gap between the adjacent edges of the facing material and to bridge this gap with gummed reinforcing and stiffening material in accordance with the details described in my Patent No. 1,596,782, August 17, 1926.

It will be noted that by using the method of the present invention for reinforcing the ends and thus simulating a plurality of folds at each extreme end of the tie, it becomes possible to avoid the use of spreading elements or other mechanical devices which often are used to maintain the shape of bow tie wings. The present invention provides a bow tie formed up from textile material and having similar material throughout the tie, thus providing for even wear with its resultant advantage as contrasted to ties in

which metallic parts tend to wear through and become conspicuous.

Referring in detail to the accompanying drawing, like parts are identified by like reference characters.

In Figure 1, there is illustrated the front view of a tie which has the general appearance of the usual bow tie. It will be observed that at the left hand side, the rear portion projects and gives the impression that one end is longer than the front bow at that side. Similarly, at the right wing the rear portion projects slightly below the front loop and gives the appearance that a hand tied bow might provide. A top plan view of the tie shown in Figure 1 is displayed in Figure 1^a. In both of these views, the front main facing material, such as silk, is indicated at 1, and 2 indicates the central tying 10 piece which is used to gather the layers together to simulate the knot of the hand tied bow tie. Referring to Figure 1^a, it will be observed that the front facing material is continued from the front around both ends 15 and along the rear, but that a peculiarity is apparent at the extreme ends where the end portions are tucked inwardly, as indicated at 1^b. It will be observed that, as in Figure 1^a, only the tip end portions are 20 tucked in and that the amount of the tucked in portion is shorter than one side of the tie from the center to either tip end.

In making up the tie of the present invention, it is preferable to use a tubular strip 25 such as is shown in Figures 4 and 5, in which the facing material 1 is folded over along its length so that its edge portions are spaced apart and provide the display portions 1^a, extending parallel to the main width 1. A 30 combined securing and stiffening strip 3 bridges the gap between the edge portions 1^a and is gummed to each of these portions. To further stiffen the strip, an inner liner 4 of stiff, coarse cloth can be used. The 35 manner in which the stiffening strip 3 is used is the basis of my Patent 1,596,782.

The method of utilizing the structure shown in Figures 4 and 5 to prepare the completed tie with the tucked-in ends will 40 now be described, with reference to Figures 6, 7 and 8 to illustrate the several steps diagrammatically. It is now intended that the tucked-in portion be prepared, and to do this, the piece shown in Figure 4 is laid face down with the strip 3 and the surface 1^a 45 downward, but with the display face 1 upward. The extreme ends of the strip are now brought together or almost together, or even overlapping slightly, as may be desired, 50 as is indicated for one end portion in Figure 6, so that the re-curved parts present adjacent faces 1 and 1 together with the faces 1^a on the outside. It is now desired to fasten 55 the adjacent faces together at a point quite 60 close to the end of the loop or folded por-

tion. This is indicated at 5 by stitching, and is accomplished ordinarily by merely running the end through a sewing machine across the width of the strip. This is performed at the two opposite ends of the folded piece. 70

The next step comprises reversing the strip so as to bring the face 1^a upward and the face 1 downward and with the sewed tucked portions 1^b projecting upward. Next, the end portions of the strip are folded toward each other as indicated diagrammatically in Figure 8. The structure is now ready to be tied together at the center by the gathering piece 2 illustrated in Figures 1 and 1^a. To most closely simulate a hand tied bow tie, the extreme end portions shown in Figure 8 may be distorted when pressed and before or after tying so as to make either the front or back projecting fold extend further out and thus give the irregularity shown in Figure 1 and suggestive of a hand tied bow tie. 80

It will be obvious that the strip shown in Figures 4 and 5 is actually tubular, even though it may include a stiffening cloth such as 4. Thus the tube of Figure 4 has two layers of facing material made up of 1 and 1^a. The cross sectional view of Figure 3 taken on the line 3—3 of Figure 1 shows that there are at least four layers of facing material. At the line 2—2 of Figure 1, the section shown in Figure 2 is taken through the extreme end portion and through the tucked-in ends of the loops, and this provides eight layers of facing material in addition to the four layers of binding or fastening material 3 and in addition to such other stiffening material as may be used and which in this case includes four layers of material 4. The stitching or other tacking or fastening means extends across the width of the strip and is shown in Figures 6, 7 and 8, extends only through the tucked-in portion, and the securing means or stitches is thus hidden by the enclosing folds of the front and rear parts of the tie. This construction provides considerable stiffness and substance to the tie at its ends, a portion which heretofore has usually been rather flimsy as compared to the other portions of the tie in known ready-made tie structures. 100

It will be observed that this tie, like hand tied bow ties, is open from top to bottom through the loops, as indicated in Figures 1^a, 2, 3 and 8. It will further be noted that the inwardly projecting tucked portion 1^b projects back into the open space. These features are in contrast to the structures of other known forms of ready made tie in which it is old to have tucked in ends which are built around a dummy padding or form, or have the folds of looped portions closed from top to bottom. 110

Any suitable fastening device may be attached at the rear to the part 2 for mounting 120 130

the necktie on a shirt collar, as is customary and this is not illustrated and forms no part of the present invention.

I claim:—

5. 1. In a bow necktie, a front facing piece across the front of the tie from end to end and continued around the opposite ends and at the rear of the tie and gathered together at the center and providing a bow tie with 10 a plurality of walls on either side of the center, said tie being open from top to bottom between said double walls giving the appearance of a plurality of separate walls on either side of center, each end of the tie 15 comprising a loop and the opposite ends being tucked inwardly away from the ends, and fastening means within the tie securing the tucked-in portion to prevent withdrawal of the same.
20. 2. In a bow necktie, a front facing piece across the front of the tie from end to end and continued around the opposite ends and at the rear of the tie and gathered together at the center and providing a bow tie with 25 a plurality of walls on either side of the center, said tie being open therethrough from top to bottom between said double walls and giving the appearance of a plurality of separate walls on either side of 30 center, each end of the tie comprising a loop and the opposite ends being tucked inwardly away from the ends and the length of the tucked in portion being less than the length of its respective side of the bow 35 of the tie, and fastening means within the tie securing one point of said tucked in portion to another point on the tie material to prevent withdrawal of the tucked in portion.
40. 3. In a bow necktie, a front facing piece across the front from end to end and continued around the opposite ends and in the rear and gathered together at the center and providing a bow tie with a plurality of walls 45 on either side of the center, said tie being open from top to bottom between said double walls, each end of the tie comprising a loop and the opposite ends being tucked inwardly away from the ends, and fastening 50 means securing the two adjacent walls of the tucked in portion of each end of the tie and said fastening means being hidden by the front and back facings of the tie.
55. 4. In a bow necktie, a front facing piece across the front from end to end and continued around the opposite ends and in the rear and gathered together at the center and providing a bow tie with a plurality of walls on either side of the center, said tie 60 being open from top to bottom between said double walls, each end of the tie comprising a loop and the opposite ends being tucked inwardly away from the ends, and stitching extending from top to bottom of

the tucked in portion and securing together 65 the two adjacent walls of the tucked in portion.

5. In a bow necktie, a center portion, wings at either side thereof and each wing comprising the front and back walls of a 70 loop and the main front and back walls of the tie, said front and back walls being open therebetween from top to bottom, and stiffening means at the end portions of the loop and comprising a plurality of folds of the 75 material of the loop extending from top to bottom at each end of the tie, the interior folds being secured together.

6. A method of making up bow neckties which method comprises treating a strip of 80 material by first folding its ends toward each other and thus forming a double layer, tacking together the double layer at points adjacent its folds, folding the strip in a direction reverse to said first fold adjacent the 85 tacked portion and with the ends of the strip in proximity to each other and in position to be secured by a central fastening piece.

7. A method of making up bow neckties 90 which method comprises treating a tubular strip of material having a display face and a plain face by tacking together folded portions of said strip with the display portion face to face and the tacking being located 95 adjacent the fold, next folding the ends of the strip to enclose the tacked folded portions and positioning said tacked folded portions substantially at the opposite ends of the tie and with the open side of the first 100 folds in opposite directions and toward the tie ends.

8. A method of making up bow neckties which method comprises treating a strip of 105 material by first folding its ends toward each other and thus forming a double layer, tacking the double layer at one point to another point on said strip to prevent unfolding of the double layer, folding the strip in a direction reverse to said first fold 110 and with the ends of said first fold within the tie.

9. A method of making up bow neckties which method comprises treating a strip of 115 material by tucking in its end portions part way only from the ends toward the center, and securing the tucked in portion at one point thereof to another point on the strip of material and within the folds whereby the tucked in portion is prevented from withdrawing, the folded portion being left open from top to bottom whereby the wings of the bow tie on either side of center have the appearance of a plurality of separate walls.

In testimony whereof I affix my signature.

OTTO WEINSTEIN.
